N° 879.

William Maurer's Design for Teggs, Part of Butteauds.

Patented March 31, 1857.

Assigned to
K. Wronkoff

Des. 879

William Mauer, of New York, N.Y.

Assignor to

R. French, of the same place.

Letters Patent No. 879. Dated March 31st 1857

The schedule referred to in these Letters Patent, and making part of the same,
To all whom it may concern:

Be it known that I, William Mauer, of the City, County, and State of New York, have invented or produced a new and original design for the legs and posts of Cast Metal Bedsteads; and I do hereby declare that the following is a full, clear, and exact description of the same; reference being had to the annexed drawings, making a part of this specification, the said drawing being an elevation of a Bedstead in a folded state; the legs and posts being of my design.

A, represents the legs of the Bedstead, the upper parts of which are formed of two leaf scrolls (a)(a).

The central portions or bodies which are surmounted

by the leaf scrolls (a) (a) have horizontal tops (b), curved uppersides (c) (c), and curved lowersides (d) (d); the lower sides (d) (d) are concave, the central portions being perforated, as shown at (e). The outer edges of the central portions or bodies are beaded, or have a moulding (f), on them; and at the edges of the lower concave sides (d) (d), a leaf edging or border (f) is formed.

To the lower parts of the central portions or bodies of the legs there is a tulip (g), and below the tulips, a fluted ornament (h), to which the scroll (i), of the castor, is attached.

On the upper parts of the leaf scrolls (a) (a), panels (j) are attached, and the posts B, are on the uppersides of the panels. The panels have each an ornament (k), at their centre; and the posts B, have a scroll bar (l) attached to their uppersides; said scroll extending down to the upper surfaces of the panels (j), at the inner sides of the posts.

C, represents a vine, which fills the space between the scroll bars (l) and the posts B. These vines are composed of roses, leaves, and smaller flowers; the leaves and portions of the vines entwining the posts B, as clearly shown in the drawing.

What I claim as new, and desire to secure by letters Patent, is;

The posts B, with scroll bars (l) and vines C; the panels (j) with ornaments (k); and the legs A, having the leaf scrolls (a) (a), leaf edging (f) (f), and the tulip and fluted ornaments (g), (h); the whole being arranged as described, to form a new and ornamental design for the legs and posts of a cast Metal Bedstead.

Witness,

W. Tuscho }
J. W. Combs }
